(54) **STEAM ENGINE, APPLICATION OF STEAM**

(76) Inventor: **Francis B. Ogden**

Granted July 11, 1869
Follows Patent

United States of America
State of New York

Seal: By this Public Instrument, I doth know to all whom the
same hath or may concern, That I, William Van Hook,
a Public Notary, in and for the State of New York, by Letters
Patent under the Great Seal of the said State, duly com-
missioned and sworn, and is and by the said Letters Pat-
ent invested with full Power and Authority to attest de-
aths, Testaments, Codicils, Agreements, and other instru-
ments in writing, and to administer any Oath or Oaths
to any Person or Persons, Do hereby certify, That on the
day of the date hereof preceding, came and appeared
before me the said notary Francis B. Ogden known to me
to be the same person named and described in the
Power of Attorney hereunto annexed and in my pres-
ence did in due form and acknowledge the same as
your usual and used for the said usual purposes herein-
before. In testimony whereof, I the said Notary have
subscribed, there present, and I have hereunto affixed
my Seal of Office, the Twenty fifth day of July, in the
year One thousand eight hundred and fifteen and of the
Independence the forty ninth.

Wm. Van Hook Not Pub.

Whereas Francis B. Ogden of the State of New Jersey in the
United States of America hath invented or discovered
a new and useful improvement in the Steam Engine
and obtained a Patent herefor from the Patent Office of
the United States in the words following to wit:

"The United States of America

To all to whom these letters patent shall come.

Whereas I, David D. Ogden, a citizen of the United States, have invented a new and useful improvement in Steam Engines and in applying Steam, which improvement he states has not been known or used before his application, hath made oath that he doth merely believe that he is the true inventor or discoverer of the said improvement hath paid into the Treasury of the United States the sum of thirty dollars, and doth make a receipt for the same, and presenteth a petition to the Secretary of State signifying a desire of obtaining an exclusive property in the said improvement and praying that a patent may be granted for that purpose.

Whereas therefore, as is according to law to the said David D. Ogden, his heirs administrators or assigns, for the term of fourteen years from the thirty first day of December One thousand eight hundred and thirteen the full and exclusive right and liberty of making, constructing, using, and vending to others to be used, the said improvement, a description whereof is given in the words of the said David D. Ogden himself in the schedule hereto annexed, and is made part of these presents.

In testimony whereof I have caused these letters to be made Patent and the seal of the United States to be thereunto affixed. Given under my hand at the City of Washington the thirty first day of December in the year of our Lord, One thousand eight hundred and thirteen, and of the Independence of the United States of America, the thirty eighth.

(Signed)

David D. Ogden

By the President

Feb. 16th 1814

City of Washington to wit,

I do hereby certify that the

Secretary of State

preparing Seller's patent, were delivered to me on the thirty-first day of December in the year of our Lord One Thousand eight hundred and thirteen to be examined that I have examined the same and find them conformable to law, and I do hereby deliver them to the Secretary of State within fifteen days of the date aforesaid to wit on the thirty-first day of December in the year aforesaid.

(Signed) Wm. Pickney, Adj. General of the United States.

The Substante reported him this Seller's patent and making part of the same, containing a description in the words of Mr. Louis Brûlé of his self of his improvement, in Steam & of his own his method of applying Steam. This improvement is predicated on the fact discovered and demonstrated by Mr. Watt, that the elasticity of steam being proportionate to its density, its expansion in being stopped off at $\frac{1}{4}$, $\frac{1}{2}$ or $\frac{3}{4}$ the capacity of the cylinder wall produces a power in a much greater ratio than $\frac{1}{4}$, $\frac{1}{2}$ or $\frac{3}{4}$ of the whole, vide Encyclopedie, 1st American edition 1st Steam plate 178 fig 16. Suppose one working my steam off whatever way in two cylinders or otherwise, so as to be stopped off at any point from $\frac{1}{2}$ to $\frac{3}{4}$ of at half the stroke. one cylinder is stopped, its steam valve is closed and that of the other is opened, or its piston arriving at the end of the stroke, that of the other will have performed half a stroke, its steam valve will then be closed and that of the first again opened as well as its opposite condensing valve, thus the motion will be regularly continued each cylinder alternately half filled with steam, and as by Mr. Watt's demonstration, stopping at one half gives a gain of 70 per cent allowing the power of steam to be equal to 100, 170 will be produced in the same time that 100 would be in a single

ey-binder - I do not confine myself to any particular
mode of the application of my process, either the working
beam. Besides, any other method now in practice may
be adopted with equal facility.

I further claim as my invention the application of
the process of the two patented in such a manner that
they shall not simultaneously be the same angle at right
angles with each other, from whence it appears that when
one is at the minimum the other, being at its maximum
will carry it past the point, and that they will mutually
tend to equalize the motion thereby doing away the necessi-
ty of balance wheels.

Witnessed (Signed)
John Reynolds
(J. H. Smith)

John B. Ogden
Now know ye that the said Francis B.
Ogden, hath, made, named, authorized, constituted, and
Appointed, and by these presents doth make, name, author-
ize, constitute and appoint Peter V. Ogden of the State
of New Jersey, in the United States of America, his true
and lawful attorney for him the said Francis, and to his
use to take out a Patent within the Kingdoms of England,
Scotland and Ireland or either of them, for the said in-
vention and to have and sell any right to any person
whatever, and generally to do, perform and execute all
and every such lawful and reasonable act, deal, matter
and thing whatsoever with respect to the said invention
as fully and effectually to all intents and purposes as the
said Francis might or could do ^{himself} if personally present.
And the said Francis B. Ogden doth hereby ratify and
promise and agree to ratify, allow and confirm, all
and what so ever his said attorney shall lawfully
do or cause to be done in the premises by virtue of

These presents, to witness whereof the said Plaintiff hath hereunto set his hand and seal this twenty-fourth day of July in the year of our Lord one thousand eight hundred and fifteen

and sixteen hundred

in the presence of,

John Moore

Not Pub.

Wm. J. Ogden (L.R.)

To all to whom these Presents shall come,

I, Thomas William Moore, Esq., of Brooklyn, in the County of Kings, New York, do hereby certify that I am York before whom the within panel of attorney was admitted in a Notary Public in the City & County of New York duly examined and appointed.

In faith & testimony whereof I the said Thos. Wm. Moore have hereunto set my hand and affixed my seal at the City of New York, this twenty-fourth day of July in the year of our Lord One thousand eight hundred fifteen.

Thomas William Moore

Notary Public
